UNITED STATES PATENT OFFICE.

LOUIS SCHUTTE, OF PHILADELPHIA, PENNSYLVANIA.

STRAINER.

SPECIFICATION forming part of Letters Patent No. 646,464, dated April 3, 1900.

Application filed January 31, 1900. Serial No. 3,410. (No model.)

To all whom it may concern:

Be it known that I, LOUIS SCHUTTE, a citizen of the United States of America, residing in the city and county of Philadelphia, in the 5 State of Pennsylvania, have invented a certain new and useful Improvement in Strainers, of which the following is a true and exact description, reference being had to the accompanying drawings, which form a part 10 thereof.

My invention relates to the construction of strainers, having for its object to provide a strainer of great simplicity and strength of construction, to provide for the ready removal 15 of the strainer proper from the casing, and to provide for a large aggregate area of strainer-perforations in a small and compact structure.

The nature of my improvements will be best 20 understood as described in connection with the drawings in which they are illustrated, and in which—

Figure 1 is a side view of my strainer, and Fig. 2 a longitudinal section taken on the line 25 2 2 of Fig. 1.

A indicates the strainer-casing, which is most conveniently of cylindrical shape, but which in no case should contract toward the end opening, which is closed by a lid.

30 A' indicates the lateral opening through the wall of the strainer-casing, which is coupled with a conduit. A² indicates an end opening, also to be coupled with a conduit and which is provided with a circumferential seat A⁷ between it and the walls of the cylindrical or substantially-cylindrical casing. A³ indicates the other end opening of the strainer, which is flush with the walls of the casing and is in use covered by a lid.

40 A⁴ indicates a flange extending out from the end of the casing in which the opening A² is formed, and A⁵ A⁵ are longitudinal flanges formed integral with the casing, on opposite sides thereof, A⁶ A⁶, &c., indicating perforated lugs, which on each side of the casing 45 extend out from its walls on opposite sides of the upper portion of the flanges A⁵, said flanges being perforated in line with the perforations of the lugs A⁶.

50 B is the lid of the casing, most conveniently formed with an annular packing-holding groove B', which fits upon the upper end

of the casing, as shown. The lid is also provided with an inwardly-extending finger B², the function of which is to engage and hold 55 the strainer, as shown, and it is also formed with two upwardly-extending lugs B³ B³ and a central rounded boss, as indicated at B⁴.

C is a U-shaped stirrup pivoted at its lower ends to a pin D, which passes through the 60 flange A⁵ and the two adjacent lugs A⁶ and is secured in place by a nut, as indicated. To the upper end of this stirrup a clamping-bar G is secured, as by means of a pin D', which would have sufficient play to permit 65 the end of the clamping-bar to rest against the top of the stirrup, as indicated in Fig. 2. The lid B is fastened to the clamping-bar by means of a pivot-pin D³, which passes through the clamping-bar and perforated lugs B³, fitting, however, with sufficient looseness to permit the clamping-bar when in use to rest and press upon the boss B⁴.

E is a U-shaped stirrup of generally similar character to the stirrup C, pivoted at its 75 lower end on the pin D², which, like the pin D, is secured to the opposite flange A⁵ and lugs A⁶. The upper end of the stirrup E has a thread perforation E' formed in it, into which screws the clamping-screw F, the lower 80 end of which when the stirrup is thrown up, as shown in Figs. 1 and 2, rests against and is screwed down upon the free end of the clamping-bar G.

H is the strainer proper, which is of frusto-conical form, its lower and broader end H' resting against the annular seat or flange A⁷, and its upper end H² having a central perforation h², into which passes the finger B² of the lid, so that the conical strainer is held in 90 place between the seat A⁷ and the lid, as shown.

l l' l² o o' o², &c., indicate perforations formed in the conical strainer, which perforations, in longitudinal lines, are arranged at gradually increasing distances from each other as they approach the smaller end of the cone, and as is shown, for instance, in the line of strainers indicated at l l' l², &c. In circumferential lines, however, the perforations are arranged at gradually decreasing distances from each other as said lines are taken at distances more nearly approaching the smaller end of the cone, and by arranging the perfora-

rations in the staggered manner indicated I am enabled in this manner to provide for the maximum number of perforations in the strainer with the least impairment of the strength of the structure and the greatest convenience for manufacturing purposes.

The construction of the casing, which avoids any contraction toward its lidded end prevents the strainer from becoming wedged in the casing, and the provision of lugs and flanges as described and shown enables the lid to be secured with great firmness to the casing and without danger of cracking or breaking the casing.

15 Having now described my invention, what I claim as new, and desire to secure by Letters Patent, is—

1. A strainer-casing A having substantially-cylindrical walls with longitudinal outwardly-extending flanges A⁵ A⁵ and lugs A⁶ A⁶ extending out on each side of said flanges in combination with U-shaped stirrup-clamps C and E pivotally secured to the flanges A⁵ and lugs A⁶ A⁶, a clamping-bar G adapted to be engaged with the stirrups C and E, a lid adapted to be held to its seat by the clamping-bar G and a strainer secured in the casing and removable therefrom when the lid is opened.
2. A substantially-cylindrical strainer-casing having one end opening A² formed with an annular flange A⁷ between it and the sides of the strainer, its other end opening A³ flush with its side walls and a lateral opening A' in combination with a lid for closing the end opening A³, means for securing said lid in place and a strainer arranged to be held in the casing between the flange A⁷ and the lid aforesaid.

3. A substantially-cylindrical strainer-casing having one end opening A² formed with an annular flange A⁷ between it and the sides of the strainer its other end opening A³ flush with its side walls and a lateral opening A', said casing having also longitudinal flanges A⁵ formed integral with the casing and extending out therefrom on opposite sides, in combination with a lid for closing the end opening A³, means for securing said lid in place and a strainer arranged to be held in the casing between the flange A⁷ and the lid aforesaid.

4. A substantially-cylindrical strainer-casing having one end opening A² formed with an annular flange A⁷ between it and the sides of the strainer its other end opening A³ flush with its side walls and a lateral opening A' in combination with a lid for closing the end opening A³, clamping mechanism for holding the lid in place secured to the upper ends of the flanges A⁵ A⁵ and a strainer arranged in the strainer-casing between the flange A⁷ and the lid aforesaid.

5. A strainer H of frusto-conical form having perforations which in longitudinal lines are arranged at gradually-increasing distances from each other as they approach the smaller end of the cone and which in circumferential lines are arranged at gradually-increasing distances as said lines approach the smaller end of the cone, all substantially as described, and so as to provide for a large aggregate area of perforations.

L. SCHUTTE.
